(57) **CLAIM**

The ornamental design for a base for bowling ball carrier, as shown and described.

DESCRIPTION

FIG. 1 is a front, top perspective view of a base for bowling ball carrier, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of detail "9" identified in FIG. 1; and,

FIG. 10 is another perspective view thereof, shown in a position of use.

The evenly dashed broken lines showing a bowling ball carrier in FIG. 10 depict environment and form no part of the claim. All other evenly dashed broken lines depict portions of the article and form no part of the claim. The dash-dot-dash broken lines in FIGS. 1 and 9 indicate the enlarged view and form no part of the claim.
